UNITED STATES PATENT OFFICE.

CHARLES A. LOWRY, OF SHAKER HEIGHTS, AND FREDERICK H. ABEL, OF EAST CLEVELAND, OHIO.

TILE WALL OR FLOOR.

Application filed July 17, 1925. Serial No. 44,287.

This invention relates to tile walls or floors.

The object of the invention is to provide an improved system or method of laying or installing tiles in a wall, floor or other place by the construction at the factory or place of manufacture of what may be termed a monolithic tile slab consisting of a plurality of tiles imbedded or set in properly arranged pattern form in a cement or other backing, such slab being of relatively large area as compared with a single tile and being suitable for application to the wall or floor, thereby not only reducing the labor of installation but also avoiding possibility of error and insuring a proper design according to the architect's specifications.

Further objects of the invention are in part obvious and in part will appear more in detail hereinafter.

In the drawings, Fig. 1 represents a plan view of a conventional tile design suitable for purposes of description of the invention; Fig. 2 is a plan view of one form of monolithic tile slab for a floor of the design shown in Fig. 1; Fig. 3 is a sectional view on the line 3-3, Fig. 2, illustrating the formation of the slab; and Figs. 4 and 5 are views similar to Fig. 2 and illustrating modifications.

In the production of a tile floor or wall, say the floor of an entry way or hallway or the wainscoting or other part of a wall, it is the custom for the architect to prepare specifications of the desired design, which specifications are submitted to the tile manufacturer who selects or forms tiles of the proper color, size and shape for the design and ships the tiles as individual pieces to the job, where the workman imbeds them separately in a cement backing and arranges them according to the pattern. The application of individual tiles in this manner requires the workman to arrange the tiles according to the desired color scheme, but most workmen are unable to follow even the most simple directions and the color arrangement more often than not is not according to specifications. Furthermore, it is exceedingly difficult to lay tiles individually and produce a finished floor surface in a single plane or without unevenness, a task which is rendered much more difficult by the considerable variance in the thickness of slate tiles. Again, in the construction of most

buildings, the builder departs in some particulars from the original specifications so that when the tile worker comes to lay a floor he finds that the surface area available to him varies a few inches one way or the other from the original estimated area. As a consequence he finds it necessary to chip and newly shape some of the tiles to preserve uniform joints between them and because the practice in laying individual tiles is to lay the border first, such newly shaped tiles occur at the center of the pattern and distort the same.

According to our invention, we propose to perform the assembly of the tiles in pattern form and arrangement at the factory by dividing a given pattern either regular or irregular according to its total area and design into a suitable number of unit fields of suitable size and shape, and assembling the tiles for a unit field upon a cement back as a monolithic slab which can be shipped to the place of installation in the same manner as a slate, marble or other panel. These tile patterns (and by tiles we are referring not to the small tiles used in more or less mosaic form in bath rooms and the like, but to relatively larger tiles, say two to four or six inches across) are never laid with a long continuous straight joint between rows of tiles. As a consequence, any given field or portion of the pattern may be of any irregular shape, having along its edges certain tiles which overlap or extend into the next adjoining field. In the construction of a monolithic slab, therefore, it is sometimes desirable to provide for such overlapping tiles.

As shown in Figs. 2 and 3, we construct the monolithic slab by laying the tiles 1 face down in proper pattern arrangement according to size, shape and color, as designed by the architect, upon a suitable smooth supporting surface, such as a metal or other plate 2. Around the tiles is placed a suitable frame 3, such as a series of wooden bars nailed or otherwise secured to each other. These wooden bars will have a thickness approximately equal to the desired total thickness of the final slab, say anywhere from one to two or more inches in thickness. Having placed the tiles within said frame and above and between the tiles is filled with plastic cement 4, which is allowed to set or harden until

the tiles are united in monolithic form. The same operation accurately fits or accommodates the frame and slab to each other. Having been laid face down upon a smooth 5 surface their exposed faces are all in the same plane. Moreover, it is immaterial whether the tiles are of the same thickness, or how much they vary in thickness, as the plastic cement is simply placed upon the 10 back of the tiles and the frame 3 is filled to its top or to the proper or desired height. Care is taken to see that the tiles are separated by the desired joints, say one-half 15 inch in width, and that the cement is forced or flows down through the spaces between tiles into contact with the supporting base 2.

The design shown in Fig. 1 has six overlapping tiles, marked 5, two along each side and one at each end. Where these overlapping tiles occur in the pattern we insert 20 blank fillers, such as the wooden blocks 6, Fig. 3, which wood blocks are of the same thickness as the slab as a whole.

Having formed the slab with wooden fillers 6 therein in the frame 3, said slab with its frame may be handled as a unit. A sufficient number of such framed slabs for the entire area is shipped directly to the place of installation, accompanied where necessary 25 by a sufficient number of loose tiles for the overlapping positions. After removing the wooden frames, which may either be taken apart or destroyed, the workman lays a suitable number of the slabs in position on the 30 floor, separating slab from slab by the necessary half-inch joint and knocking out the wooden fillers 6 and replacing the same by the loose overlapping tiles supplied to him. It is therefore necessary to insure only that 35 the smooth plane surfaces of adjacent slabs are in the same plane with each other. The slabs are laid or imbedded in a relatively thin sub-base of cement or the like. Also, in laying these slabs, a central or patterned 40 portion of the floor or wall is first applied and the border is laid in position around the central or patterned portion. Irregularities in the construction of the building can therefore be compensated for in the border by 45 chipping or properly shaping the border tiles and adjusting the joints between them.

If desired, any slab of irregular shape can be handled in the manner shown in Fig. 4, by shaping or accommodating the frame to 50 the slab. In the form shown, the slab is provided with overlapping tiles 5^a along two sides of a generally rectangular pattern, which tiles have an extra width equal to the width of the joints between tiles, say one-half 55 inch. These extra wide tiles consequently extend beyond the border of the slab and the side frame members 3 are suitably formed or arranged, such as by being recessed, to accommodate them to the peculiar 60 shape. Also, if desired, complete or full-

sized overlapping tiles 5^b may be provided along two edges, as in Fig. 5, and the frame 3 may be made larger to take up the extra size, any open spaces being filled with wooden fillers 7, which are removed with the 70 frame when the slab is laid in place in the floor. In this arrangement, no loose tiles need be shipped, but each field or slab carries half of the overlapping tiles adapted to mate or fit with corresponding recesses in the next adjoining field. With the tiles shown in Fig. 4, the extra half-inch on some of the overlapping tiles enables them to closely abut corresponding tiles in the next field with a closed joint in which there is no 80 cement, as will be obvious. Other arrangements are suitable for the purpose.

The invention described insures accuracy in the reproduction of the architect's pattern by the proper distribution of different colored tiles by skilled workmen at the factory. It also ensures an absolutely smooth, uniform plane surface on the entire floor or wall area and enables irregularities in the available floor area to be compensated for in the 90 border instead of in the pattern center.

Other advantages will be apparent to those skilled in the art.

Having described our invention, we claim:

1. As an article of manufacture, a framed tile slab, comprising a tile facing, a removable surrounding frame, and a backing of hardening plastic material cast while plastic within said frame and behind said facing, said frame thereby accurately fitting the 95 monolithic slab within it and protecting the same during handling and shipping, and said slab upon removal of said frame being adapted for assembly with others to form a tile surface.

2. As an article of manufacture, a framed tile slab, comprising a frame open on both faces, a plurality of tiles lying within said frame with their exposed surfaces in a common plane, and a backing of hardening plastic material cast while plastic within said frame and around said tiles to permanently 100 secure the tiles to each other as a monolithic slab and to also accurately fit said slab to the frame, said frame serving to protect the slab during handling and transportation and being removable from the slab, whereby the latter may be assembled with others to form a continuous tile surface.

3. As an article of manufacture, a framed tile slab, comprising an open frame including a series of connected members of uniform thickness approximately equal to the desired slab thickness, a tile facing within said frame with its exposed face in approximately the same plane with one of the frame faces, and a backing of hardening plastic material filling the frame and the space behind the tile facing with its backing surface 115 in approximately the same plane with the 120

opposite surface of the frame, said frame thereby accurately fitting the monolithic slab within it and protecting the same during handling and shipment and being removable from the slab, whereby the latter may be assembled with others to form a continuous tile surface.

4. The method of forming a patterned tile wall or floor, consisting in sub-dividing the pattern into unit areas of a size and shape convenient for handling, forming a surrounding open frame for each unit area, ar-

ranging the proper tile facing within each frame, applying hardening plastic backing to the backs of the tile facings to thereby fill the several frames and form framed monolithic slabs, removing the frames, and assembling the slabs upon a common backing to form the wall or floor.

In testimony whereof we hereby affix our signatures.
